(57) **CLAIM**

The ornamental design for a shower control panel, as shown and described.

DESCRIPTION

FIG. 1 is a front, top and left perspective view of a shower control panel showing our new design;
 FIG. 2 is a front, top and right perspective view thereof;
 FIG. 3 is a front view thereof;
 FIG. 4 is a top view thereof;
 FIG. 5 is a left side view thereof; and,
 FIG. 6 is a right side view thereof.

A rear view and a bottom view are omitted since the rear view and the bottom view are invisible in normal use.
 The broken lines depict portions of the shower control panel in which the design is embodied that form no part of the claimed design.
